UNITED STATES PATENT OFFICE.

WARREN W. BRIGGS, OF PROVIDENCE, RHODE ISLAND, ASSIGNOR TO
S. & B. LEDERER, OF SAME PLACE.

DESIGN FOR AN ORNAMENTAL CHAIN.

SPECIFICATION forming part of Design No. 12,951, dated May 30, 1882.

Application filed March 13, 1882. Term of patent 7 years.

To all whom it may concern:

Be it known that I, WARREN W. BRIGGS, a citizen of the United States, residing at Providence, in the county of Providence and State of Rhode Island, have invented and produced a new and original Design for Ornamental Chains, of which the following is a full, clear, and exact description, reference being had to the accompanying drawings, forming part of this specification.

Figure 1 is a face view of my newly-designed ornamental chain, and Fig. 2 is a side or edge view of the same.

The leading feature of my newly-invented design in ornamental chains consists in a raised wire or band having two sides extending from the center of the chain outward, so as to give to the chain a herring-bone appearance, as is shown in Fig. 1.

In the drawings, A A are the links, B B are the connecting-links, and C C are the herring-bone wires. These wires are raised above the face of the links A and branch outward to

the edge of the chain. They may be made of round or flat wire. They may be ornamented or made of different metal than the chain proper, or of metal having the same or a different color than the rest of the chain. They form bifurcated ornaments on the links and impart to the chain a new, ornamental, and easily-distinguishable appearance, giving to the same a herring-bone appearance. These bifurcated bands or wires may be used on one or both sides of the chain.

Having thus described my newly-invented design, I claim as new and desire to secure by Letters Patent—

The design for an ornamental chain herein shown and described, the same consisting of the herring-bone or bifurcated raised ornaments C, in connection with the links A and connecting-links B.

WARREN W. BRIGGS.
